J. Reaney Kelly, Attorney

UNITED STATES PATENT OFFICE.

JOHN D. SHAFFER, OF SALT LAKE CITY, UTAH.

AUXILIARY SLED RUNNER.

Application filed March 29, 1921. Serial No. 456,620.

To all whom it may concern:

Be it known that I, JOHN D. SHAFFER, citizen of the United States, residing at 956 Edison St., Salt Lake City, in the county 5 of Salt Lake and State of Utah, have invented certain new and useful Improvements in Auxiliary Sled Runners, of which the following is a specification.

The present invention relates to improvements in sleds and more particularly to auxiliary sled runners which, when operatively associated with a sled of conventional type will enable the same to be used for coasting on streets and side-walks.

15 The main object of the invention is to provide auxiliary sled runners which may be quickly and easily attached or detached to or from the runner of a sled of conventional form so that the conventional sled 20 may be easily converted for the purpose set forth above.

A further object of the invention is to provide a sled runner of the above type which is simple in construction, strong and durable and which, it is believed, may be manufactured at a reasonably low cost.

Various other objects and advantages of my invention will become apparent during the continuance of the following description.

In the drawings:

Figure 1 is a view in side elevation of my invention shown operatively associated with a sled of conventional form.

35 Figure 2 is a view in bottom plan of a sled equipped with the improved device of my invention.

Figure 3 is a view in bottom plan of the main or body portion of the auxiliary runner.

40 Figure 4 is a view in transverse cross section taken on line 4-4 of Figure 1.

Inasmuch as both of the auxiliary runners herein shown, for purposes of illustration, are substantially of the same construction, only one will be described in detail.

The main or body portion 10 of the auxiliary runner is of suitable length, width and thickness and may be constructed of 50 any suitable or desirable material. It is of sufficient length to extend over practically the entire engaging surface of the main sled runners and is suitably curved throughout its length to fit snugly against the under 55 side of the sled runners and to compensate

for the curvature thereof near the front end of the sled.

On its under side the body portion 10 is provided with spaced receiving cavities 11 for accommodating suitable anti-friction 60 means shown in the present embodiment in the form of ball bearings 12. These receiving cavities, however, accommodate only a little more than one-half of each roller bearing as clearly shown in Figure 1 and other 65 means is provided to maintain the roller bearings in place, as will be hereinafter set forth.

Adjacent its ends, the under side of the body portion 10 is cut away as at 13 to receive the transverse portion 14 of a clamping member 15 whose arms embrace the body portion 10 and the sled runners as will be more clearly described hereinafter.

The under side of the body portion 10 is 75 further provided with a series of spaced openings 16 which receive suitable fastening means.

On its under side, the body portion 10 receives a metallic plate 17 that extends 80 throughout its entire length and which is secured in place by fastening means 18 that enter the opening 16 of the body portion. The plate 17 is further provided with spaced openings 19 through which the ball bearings 12 project and in view of their being of less diameter than the ball bearings, it will be observed that the latter will be maintained in place by means of the plate 17.

The plate 17 also spans the cut away portions 13 as shown in Figure 4 thereby preventing loss of the clamping members 15 after the auxiliary runner has been removed from the sled.

For purposes of illustration, I have shown, 95 in the present embodiment, a sled comprising a body portion 20 which is equipped with the usual steel runners 21. When in place, the body portion 10 of the auxiliary runner fits snugly against the under side of 100 the main runner 21, as shown in Figure 1, while the clamping members 15 embrace both the body portion 10 and the runner 21, as clearly shown in Figure 4. By tightening the fastening means 22, the clamping 105 members may be firmly locked in position and the auxiliary runner held rigid with relation to the main runner 21. From this it will be observed that the operation in attaching the auxiliary runner or detaching 110

the same to or from the main runner 21 is simple and easy and that after the auxiliary runner is in place, not only does the sled retain its normal contour but is converted 5 whereby it may be used for coasting or on sidewalks or streets.

- It is to be understood that I do not limit myself in any way to the specific form of materials used in the construction of any 10 of the parts of my invention nor do I limit myself to the specific construction of the anti-friction devices 12. It is believed that rollers or ball bearings can be used to the same advantage.
- 15 From the foregoing it is believed that the advantages and novel features of my invention will be readily understood and therefore further detailed description is deemed unnecessary.

20 What is claimed is:

1. An auxiliary sled runner comprising a main or body portion adapted to be disposed lengthwise over the engaging surface of a sled runner and presenting spaced cavities in its under side, anti-friction bearings seated in said cavities, clamping members straddling the said body portion and having engagement with the said sled runners to secure the body portion thereto, and a

metallic strip extending lengthwise of the 30 under side of the said body portion and fastened thereto for confining the said bearings and clamp members in place on the said body portion, said strip having openings thru which the said anti-friction bearings operate.

2. An auxiliary sled runner comprising a main or body portion adapted to be disposed lengthwise over the engaging surface of a sled runner, said body portion having 40 its under side provided with circular cavities and transversely extending cut-outs, clamping members seated in the said cut-outs of the body portion and straddling the latter to engage the runner of a sled on opposite sides for securing the body portion in place, ball bearings seated in the circular cavities of the said body portion, and a metallic strip extending lengthwise of the body portion and secured to the latter on its 50 under side to cover the said cut-out and cavities for retaining the said clamp members and ball bearings in place, said strip having openings thru which the said ball bearings operate.

55 In testimony whereof I affix my signature.

JOHN D. SHAFFER.
